UNITED STATES PATENT OFFICE.

JOSEPH L. FRIEDMAN, OF CHICAGO, ILLINOIS.

HEATER.

SPECIFICATION forming part of Letters Patent No. 689,958, dated December 31, 1901.

Application filed March 16, 1901. Serial No. 51,439. (No model.)

To all whom it may concern:

Be it known that I, JOSEPH L. FRIEDMAN, a citizen of the United States, residing at Chicago, in the county of Cook and State of Illinois, have invented a certain new and useful Improvement in Heaters, (Case No. 1,) of which the following is a full, clear, concise, and exact description, reference being had to the accompanying drawings, forming a part 10 of this specification.

My invention relates to heaters, and has for its object the provision of an improved form of heater that will furnish a moist heat.

The heater of my invention is a hot-air heater wherein the air is heated, preferably, by a number of burners, the heat from the burners being conveyed through suitable flues. A plurality of flues is preferably employed for the burners, one for each flue, a 15 water-chamber surrounding the upper portions of these flues, while the burners are preferably located in the lower parts thereof. The water-chamber is common to all of the flues, so that, in effect, a single body of water 20 is subjected to the heating action of a given number of separate gas-flames. By this arrangement the water is vaporized not only through the agency of the heat as it passes 25 through the flame-flues, but is also heated 30 by the hot gas and air that by means of my construction may find access to the upper surface of the water. The vapor may pass through vapor-flues that are preferably located in line with the flame-flues and which 35 communicate therewith, the upper ends of the vapor-flues being open to the extraneous atmosphere. In order that the vapor and the heat may be properly directed into the room in a manner to prevent the irregular distribution thereof, I provide a cap that serves to bring about an intermingling of the vapors, &c., from the various flues before they are 40 passed into the outer air.

The heater of my invention is particularly 45 well adapted for use where gas-heaters are employed, although the invention is not to be limited to this particular service.

I will explain my invention more fully by reference to the accompanying drawings, in 50 which—

Figure 1 is a perspective view of a heater constructed in accordance with my invention,

and Fig. 2 is a cross-sectional view on line 22 of Fig. 1.

Like parts are indicated by similar characters of reference in the views.

The base *a* of the burner may be of any suitable form to give the required stability to the structure. A suitable means for conveying fuel extends longitudinally of the heater, 55 which means is preferably in the form of a gas-pipe *b*, from which a number of gas-jets *c* project. The flow of gas to the pipe *b* may be controlled in any suitable way, as by means of a main cock *d*. The base of the 60 burner supports a series of flame-flues *e*, each of which preferably contains a single gas-jet *c*. These flame-flues are preferably open at both extremities and are inclosed by a ledge *f*, upon which the water-chamber *g* and the 65 vapor-flues *h*, carried by the water-chamber, 70 may be removably secured to light the gas-jets. Other means may also be employed for lighting the gas-jets. The water-chamber *g* is preferably common to all of the gas or flame 75 flues and also to the vapor-flues, free access being had between both sets of flues and the water-chamber. The flues *e* and *h* are preferably placed in alinement. The heat serves to vaporize the water not only through the communication of heat from the flame through the walls of the flues *e*, but also by contact 80 of the heated air with the upper surface of the water, so that the requisite moisture may be imparted to the heated air as it passes into 85 the room. The water may from time to time be replenished through the spout *i*. The vapor and heated air passing through the vapor-flues *h* are momentarily assembled within the space *k* afforded by the cap *l*, which is 90 provided for this purpose. In order that the space *k* may have communication with all of the flues *h*, the cap *l* is mounted upon supports *m*, that serve to maintain the cap a proper distance above the vapor-flues without 95 impairing this communication.

By providing a plurality of flame-flues and a plurality of vapor and hot-air flues not only is the desired vaporization of water secured in a most effective manner, but I increase the radiating-surface afforded by the large exposed outer surfaces of the flues. By this arrangement a very effective heating apparatus may be produced which is devoid of 100

the many objections that are usually urged against heaters of this type.

I prefer the particular relative arrangement of the various parts of the heater herein set forth; but I do not wish to be limited to the precise details of construction shown, as it is obvious that modifications may readily be made without departing from the spirit of my invention.

10 Having thus described my invention, I claim as new and desire to secure by Letters Patent—

15 1. In a heater, the combination with means for producing a plurality of flames, of a plurality of flame-flues for separating the flames, a water-chamber surrounding the flame-flues and common to same, the flues projecting through the bottom of the water-chamber, whereby a space is afforded between the water-chamber and the flues for the reception 20 of water, the said flame-flues being open at their upper ends whereby the water may be heated by the flames through the material of the flues and by contact of the heated air with the upper surface of the water, vapor-flues 25 open at their ends and having communication with the water-chamber at their lower

ends, and a cap *l* affording a space *k* within which the heated vapor, &c., from the flues of the heater may be gathered and then forced into the outer air, substantially as described.

2. In a heater, the combination with means for producing a plurality of flames, of a plurality of flame-flues for separating the flames, 30 a water-chamber surrounding the flame-flues and common to the same, the flues projecting through the bottom of the water-chamber, whereby a space is afforded between the water-chamber and the flues for the reception 35 of water, the said flame-flues being open at their upper ends whereby the water may be heated by the flames through the material of the flues and by contact of the heated air with the upper surface of the water, and vapor- 40 flues also in communication with the water-chamber and having communication with the outer air, substantially as described.

In witness whereof I hereunto subscribe my name this 27th day of February, A. D. 1901. 45
JOSEPH L. FRIEDMAN.
